(57) **CLAIM**

The ornamental design for a hand held relaxation device, as shown and described.

DESCRIPTION

FIG. 1 is a three dimensional view of the first embodiment of the hand held relaxation device.

FIG. 2 is a three dimensional view of the hand held relaxation device.

FIG. 3 is a side view of the hand held relaxation device.

FIG. 4 is a side view of the side opposite the side shown in

FIG. 3.

FIG. 5 is a front view of the hand held relaxation device.

FIG. 6 is a back view of the hand held relaxation device.

FIG. 7 is a top view of the hand held relaxation device.

FIG. 8 is a bottom view of the hand held relaxation device.

FIG. 9 is a three dimensional view of the second embodiment of the hand held relaxation device.

FIG. 10 is a three dimensional view of the hand held relaxation device.

FIG. 11 is a side view of the hand held relaxation device.

FIG. 12 is a side view of the side opposite the side shown in FIG. 11.

FIG. 13 is a front view of the hand held relaxation device.

FIG. 14 is a back view of the hand held relaxation device.

FIG. 15 is a top view of the hand held relaxation device; and,

FIG. 16 is a bottom view of the hand held relaxation device. The broken lines depicting the hand in FIGS. 1 and 9 and the broken lines in FIGS. 1-7 on the top of the hand held relaxation device form no part of the design of FIGS. 1-7 and 9 and are included for the purpose of illustrating environment.
